UNITED STATES PATENT OFFICE.

CHARLES DANIELSON, OF MINNEAPOLIS, MINNESOTA.

SADIRON SUPPORT.

Application filed December 17, 1926. Serial No. 155,416.

My present invention has for its object to provide an insulating sad iron support.

To the above end, the invention consists of the novel devices and combinations of devices hereinafter described and defined in the claim.

In the accompanying drawings, which illustrate the invention, like characters indicate like parts throughout the several views.

10 Referring to the drawings:

Fig. 1 is a front elevation of the invention mounted on a kitchen table;

Fig. 2 is a fragmentary bottom plan view of the ironing board;

15 Fig. 3 is a fragmentary plan view of the ironing board, at its wide end, and the sad iron support on an enlarged scale;

Fig. 4 is a view in longitudinal central section taken on the line 4—4 of Fig. 3; and

20 Fig. 5 is a view in transverse section taken on the line 5—5 of Fig. 4.

The improved ironing board is indicated by the numeral 6 and has rigidly secured to its underside, at the wide end thereof, a 25 transverse end bar 7 and two side bars 8. Said bars 7 and 8 are set edgewise in triangular arrangement, and the side bars 8 have their lower edge portions shaped to afford pairs of longitudinally spaced legs 9, adapted to rest on the top of a kitchen table 10. On the bottoms of the legs 9 are rubber pads 11 which prevent said legs from slipping or scratching the top of the table 10. The length of the legs 9 is such as to support the ironing board 6 in a convenient 35 ironing position when on a table top.

The arrangement of the side bars 8 is such that the greater part of the ironing board 6 is free and spaced above the top of the table 40 10 so that a skirt or dress may be conveniently ironed thereon.

To prevent the ironing board 6 from tipping under the pressure applied during ironing action, said ironing board at its wide end is secured to the top of the kitchen table 10 by an L-shaped clamping plate 12 the horizontal portion of which underlaps and engages said table top. Said clamping plate 12 is adjustably and longitudinally secured to the end bar 7 by a thumb nut 45 equipped bolt 13 mounted in a bore in said bar and extending through a vertical slot 14 in the vertical member of the clamping plate 12. Obviously, the slot 14 permits the clamping plate 12 to be adjusted for table tops of different thicknesses.

The ironing board 6 at its wide end, has formed therewith an extension 15 which forms a base member for a sad iron support, as will presently appear. The width 60 of the extension 15 is materially less than that of the ironing board 6, and the upper face thereof is spaced below the upper face of the ironing board 6. A U-shaped up-standing metal frame 16 overlaps the sides 65 and outer end of the extension 15 and is secured thereto by nails 17 or other fastening devices. The frame 16 extends above the top of the ironing board 6 to afford an iron stop, and the side portions thereof have 70 their upper edges beveled to meet the top of the ironing board 6.

An insulating sheet 18 of asbestos or other heat resisting material rests on the extension 75 15 and an open mesh corrugated metallic sheet 19 rests on said sheet 18, and which sheets 18 and 19 are of such size as to snugly fit within the frame 16 and adjacent end of the ironing board 6 and be held in position thereby. Supported on the metallic sheet 19 is an insulating sad iron supporting pad 20, the top of which is flush with the top of the ironing board 6. The insulating sad iron supporting pad 20 is preferably but not necessarily of the same material as the pad 18 but considerably thicker and is spaced from the respective end of the ironing board 6 and the frame 16 to afford an air gap 21 therebetween. Said supporting pad 20 is secured in position by 80 nails driven into the extension 15. The corrugations in the sheet 19 extend both longitudinally and transversely thereof so that air is free to circulate both above and below the same through the air gap 21, 85 and thereby always keep the insulating pad 20 cool. As previously stated, the top of the sad iron supporting pad 20 is flush with the top of the ironing board 6 so that the iron may be moved onto and off from said 90 pad by a sliding action without having to lift the same, thereby materially reducing the work of the operator.

On the bottom of the extension 15 is a spring clip 22 for holding the separable 105 socket of an electrical cord for a sad iron.

By supporting an electric iron with its ironing surface directly on the insulating pad 20, said iron will retain the heat stored therein and hence will always be ready for use and there is no time lost in waiting for the iron to heat, after being used; further-

more, the electrical current to the iron may be cut off quite a while before the ironing is completed for the reason that when the iron is not in use and resting on the insulating holder 20, the heat stored therein will not be carried off.

By mounting the sad iron supporting pad 20 on metal and spacing the same from an ironing board for the circulation of air thereunder and therearound, makes the sad iron support fire proof and this eliminates all danger of starting a fire by the overheating of an electric iron.

What I claim is:

A sad iron holder comprising a base member having a marginal frame affording a sad iron stop, an insulating sheet on said member, an open mesh metal sheet on the insulating sheet, and an insulating supporting pad on the metal sheet, said metal sheet being longitudinally and transversely corrugated to permit the circulation of air both above and below said metal sheet, said pad being spaced from the frame to afford an air gap.

In testimony whereof I affix my signature.

CHARLES DANIELSON.
